TIE RACK

Filed Feb. 6, 1931

John H. Horstman,
INVENTOR,
Howard S. Smith,
BY His ATTORNEY

UNITED STATES PATENT OFFICE

JOHN H. HORSTMAN, OF DAYTON, OHIO

DESIGN FOR A TIE RACK

Application filed February 6, 1931. Serial No. 38,572. Term of patent 3½ years.

To all whom it may concern:

Be it known that I, JOHN H. HORSTMAN, a citizen of the United States, residing in the city of Dayton, in the county of Montgomery and State of Ohio, have invented a new, original, and ornamental Design for a Tie Rack, of which the following is a specification.

The figure is a perspective view of a tie rack, showing my new design.

I claim:

The ornamental design for a tie rack, as shown.

JOHN H. HORSTMAN.
